PROCESS OF PRODUCING SHOES

Alan E. Murray, New York, N. Y.

Original application September 17, 1945, Serial No. 616,768. Divided and this application December 1, 1949, Serial No. 130,455

5 Claims. (Cl. 12—142)

1

My invention relates particularly to a process of making shoes which adequately and effectively fit the feet of the wearer for which they may be made.

This application is a division of my copending application upon Process of Producing Shoes and Product Thereof, Ser. No. 616,768, filed September 17, 1945, now abandoned.

The object of my invention is to provide a method of making shoes which closely conform to, or accurately fit, the individual feet for which they are made. Another object is to provide a method of making shoes which may be made expeditiously and at a comparatively low cost. Still another object of my invention is to provide a process which not only produces an accurate fit for the individual feet for which the shoes are made, but of such a character as to make it possible for the individual person even to make shoes to accurately fit his own feet. A further object is to provide a process by means of which the shoes not only fit the feet with accuracy but which assume a conformation according with the natural angular positions of the feet with regard to the supporting surface of the ground. Again, a further object is to produce the shoes in such a manner that they not only acquire a static shape of the feet, but have the dynamic conformation of the feet in action. Further objects of my invention will appear from the detailed description of the same hereinafter.

While my invention is capable of being carried out in many different ways, for the purpose of illustration I have shown only certain ways of carrying out the same in the accompanying drawings, in which—

Fig. 1 is a side perspective of a shoe made in accordance with my invention, showing the outer side of the shoe made for the left foot;

Fig. 2 is a vertical cross-section of the same;

Fig. 3 is a plan view of the same;

Fig. 4 is a plan view of two monks cloth layers used in making a pad in producing the shoe;

Fig. 5 is a perspective view of the two sheets in Fig. 4, joined together;

Fig. 6 is a plan view of a paper sheet used in making a pattern;

Fig. 7 is a plan view of a cut-out paper pattern, shown as applied over the double layer of monks cloth made from the two monks cloth layers shown in Fig. 4;

Fig. 8 is a plan view of a cut-out double sheet of the monks cloth conforming to the paper pattern shown as placed above another sheet of monks cloth having a wide margin around the foot-shaped double sheet of monks cloth;

2

Fig. 9 is a plan view showing a transverse opening which was cut through one layer of the monks cloth preparatory to stuffing the pad formed from the three layers of monks cloth;

Fig. 10 is an end elevation of the layers shown in Fig. 8;

Fig. 11 is a plan view of the completed pad conforming to the shape of the foot after the same has been stuffed with a suitable filling material;

Fig. 12 is a vertical section of the stuffed pad in its inverted position;

Fig. 13 is an inverted plan view of another wider layer of monks cloth, shown as ready to be applied over the pad after completion of the latter;

Fig. 14 is a plan view of a top front piece of monks cloth provided to overlie the front upper portion of the foot;

Fig. 15 is a plan view of a monks cloth counter piece for covering the back of the foot;

Fig. 16 is a plan view of a counter reinforcing strip;

Fig. 17 is a plan view of an eyelet strip to be located over the topmost ridge at the front of the foot;

Fig. 18 is a side elevation of the shoe showing the top front piece and the rear counter piece as well as the counter reinforcing strip located in place;

Fig. 19 is a cross-sectional detail taken on the line 19—19 of Fig. 18 showing the pad located in the upper;

Fig. 20 is a horizontal section showing the joining of the front top piece and the counter piece;

Fig. 21 is a plan view showing the eyelet strip located in place;

Fig. 22 is an underneath view of the shoe, partly broken away, after the removal of the pad therefrom, preparatory to completing the lower portion of the shoe;

Fig. 23 is a horizontal section showing the front top piece and the heel piece as well as the outside cover pieces; and

Fig. 24 is a vertical section showing the bottom of the shoe ready to receive the mud.

In carrying out my invention I provide a pad made, as shown in Fig. 4, with two sheets of monks cloth 2 and 3, each of which is supplied on one side with a coating of a self-vulcanizing latex or self-vulcanizing synthetic rubber substitute, as for instance neoprene, or a self-vulcanizing vinyl resin, which is in the form of a liquid, preferably of a heavy character having the consistency of a very heavy cream. This liquid

latex, which is a water suspension of the rubber or rubber substitute prepared so as to be self-vulcanizing, is then allowed to set. Thereafter, I brush onto the coated sides of the respective monks cloth sheets 2 and 3 a thin tacky coating of rubber cement and fasten them to each other by bringing the coated faces together, Fig. 5.

The person for whose feet the shoes are to be made is then seated on a chair, located preferably on a table, so that his feet are supported on the top of the table. Thereupon, a sheet of paper 4 is placed on the table under each of the feet and an outline 5 is made on each of said sheets by running a pencil point around and vertically beneath the edge of each foot. Inasmuch as the shoes for both feet are made in the same manner, the making of only one of the shoes will be described in detail herein. After the outline 5 has been made for the right foot on the sheet of paper 4, the sheet is pulled from under the prospective user's foot and the letter R is placed in pencil thereon so as to avoid any possible interchange or inversion of the patterns for the two feet in the course of making the two shoes. As shown, for example, in my Patent No. 2,396,926, March 10, 1946, a new heel line 6 may be made to give the support for the foot additional length and additional width, as shown in Fig. 6. Also, as shown in said patent, a new instep line 7 may be drawn well inside the pencil outline 5, for example, as shown in Fig. 6, about where the foot contacts with the sheet of paper. Thereupon a pattern 8, with the changed outlines 6 and 7, is cut therefrom with a pair of scissors. This pattern 8 is then cemented, with rubber cement, to a composite sheet 9, made as stated above, that is, by combining the two coated sheets 2 and 3, and this double sheet 9 is cut out around the margin of the paper pattern 8 so as to produce a double sheet 10 having a shape which conforms to the changed contours of the outline 5 of the foot. A mark R should then be placed on the same after stripping off the paper pattern 8, to avoid interchange or inversion thereof. The double sheet 10, conforming to the altered outline of the foot, as shown in Fig. 10, is then placed over another piece of monks cloth 11, which latter is thereupon cut out with a margin substantially 1" wide all around the double sheet 10, as shown in Fig. 8. The remaining portion of the element 11 is then dissociated from the sheet 10 and powdered plaster of Paris is then dusted over one face of the wide layer 11 so that, after this dusting, the face with the plaster of Paris, upon being placed into contact with the latex remaining on one face of the double sheet 10 after the stripping of the paper pattern 8 therefrom, will cause the latex to set more rapidly by the withdrawal of water, etc. The margin of the wide layer 11 is brushed over the surface thereof with latex all around the margin of the dusted face, and, in addition, the latex is applied from the edge of double sheet 10 to about the same distance 1" within the margin of the exposed face of the double sheet 10 all around the same. The margin of the sheet 11 is now bent over the edge of the double sheet 10 all round the same onto the margin of said latex-treated exposed face of the double sheet 10, as shown in Fig. 9, and a number of puckers radiating around the folded-in margin of the layer 11 are formed, one preferably opposite the big toe, another opposite the rear of the heel, two more at the sides of the heel, and two more, one at the side and the other at the front por-

tion of the composite sheet. Any number of such puckers may be formed in this way, but usually from 6 to 12 of such puckers will be found sufficient, so that in this way each of the puckers can be pinched between the fingers and pushed out around the margin of the double sheet 10 so as to squeeze out any excess liquid. All of these puckers are now cut off with a scissors so that the resistant edges meet and the folded-in margin of the layer 11 fits together accurately around the margin of the double sheet 10, as shown in Fig. 9. When the latex is set sufficiently, a transverse slit 12 is made across the shank or thereabouts on the side of the sheet 10 carrying the folded over margin of the layer 11, the said slit 12 being made with a scissors or razor blade so as to cut through only one of the layers 2 and 3. Thereafter, a knife is inserted through the slit 12 between the two layers 2 and 3 to separate them throughout the whole area of the sheet 10, thus loosening up the cement between the two layers 2 and 3. The cavity now formed between the two layers 2 and 3 is then stuffed, preferably by over-stuffing, tightly so as to produce a very firm pad with any suitable stuffing materials. I may use for this purpose, for example, a body of finely divided material such as cotton flocking containing short fibres to form a flowable filling material, the said fibres having been previously subjected to bleaching and solvents to remove the oil and other foreign materials from the cellulose fibres. Or, instead, for example, the pad can be stuffed with sand, wood, flour, or sawdust, etc. The slit 12 is then sealed over with a monks cloth layer 13 fastened in place by rubber cement. In order to distribute uniformly the materials in the pad, it is hammered repeatedly or beaten with a 2 x 4" piece of wood of any desired length. Or, instead, I may stuff the pad with a mud of latex and wood flour, etc., having a flowable consistency which will set, to form a solid, so as to accurately fit the bottom of the foot. The mud may be made like the mud hereinafter described in respect to the making of which the application is a continuation in part of my copending application upon Process of Shoe Making and Product Thereof, Ser. No. 448,474, filed June 25, 1942, now Patent No. 2,396,926, granted March 19, 1946. The pad made in this way may, if desired, remain as a pad in the completed shoe, in which event the layer of monks cloth 14, hereinafter referred to, will be omitted and the application of the mud to fill in the cavity in said monks cloth 14, as hereinafter referred to, will likewise be omitted. However, the completed shoe in other respects will remain the same as hereinafter described as when the pad 9 has been removed.

I now provide another piece of monks cloth 14 conforming in general to the margin of the foot but wider than the layer 11 after the margin of the latter has been folded in, the underside of this layer 14 being dusted with plaster of Paris and placed over the pad 1 with its margin extending outwardly of the pad 1, the latter being provided with a marginal coating of latex 15 extending all around the pad 1 but below the plane of greatest width of the inverted position of the pad, as shown in Fig. 13. The foot is then placed on top of the layer 14 while being pressed down with the weight of the foot and leg, while being supported on the pad. The layer 14 is now pushed up by the fingers between the respective toes of the foot and into the transverse space between the rear ends of the toes of the prospective wearer while momentarily

raising an edge of the foot, preferably at the front of the foot, together with the layer 14, from the pad 1, thus resulting in the formation in the layer 14 of a pyramid 16 beneath the foot at the area where the toes join the ball of the foot. While the foot is still on the top of the layer 14 covering the pad 1, the marginal edges of the layer 14 are then moved downwardly around the periphery of the pad 1 carrying the latex layer 15 so as to stick the said margins to said latex layer 15 extending around the pad 1. Thereupon a layer of the latex is applied all around the outer margin of the layer 14 on the pad 1 and a roughly oversize top front piece of monks cloth 17 is now cut out, of such a shape that it has a curved recess 18, and is positioned on the foot and located opposite the front part of the ankle, with two straight edges 19 and 20 extending vertically along the sides of the ankle. This top front piece 17 is now caused to adhere to the latex around the outer margin of the layer 14 (Figs. 13 and 19), the toe portion of the piece 17 is puckered so as to fit on the front of the big toe of the foot and this puckered portion is then cut off, leaving a V-shaped cut out 21, as shown by the dotted line in Fig. 14, the two sides of which cut out, however, meet over the front of the big toe. Preferably, before the top front piece 17 is thus applied to the foot it will be dusted on the underside, with plaster of Paris, where it comes in contact with the latex applied to the layer 14 to accelerate the setting of the latex. A roughly oversize counter piece 22 of monks cloth is now cut out and dusted on the underside margins, with plaster of Paris, where it comes in contact with the latex on the margin of layer 14 and the vertical marginal portions of the front top piece 17 are brushed with the latex, following which the counter piece 22 is applied over the heel of the foot so that the same adheres to the rear of the pad 1 and to the vertical marginal portions 19 and 20 of the front piece 17. Thereupon, a counter and quarter reinforcing piece 23 of monks cloth is cut out and after being dusted on the underside with plaster of Paris, and the side and rear portions of the front piece 17 and the counter piece 22 having been brushed with latex, the counter reinforcing piece 23 is fastened in place around the rear and side portions of the pieces 17 and 22. It will be understood that all these pieces 17, 22 and 23 preferably extend at their lower edges only down to the line extending all around the pad at the widest portions of the pad 1. Next, I cut out an eyelet strip 24 of monks cloth which is dusted on the underside with plaster of Paris and fastened onto the highest or ridge line of the front of the foot by latex, which is applied over the corresponding portion of the front piece 17 for this purpose. The front end of the eyelet strip 24 extends down over the top of the big toe. Two pieces of terry cloth 25 and 26 are now made of the same shape and size as the pieces 17 and 22 so that their lower edges can be puckered and cut out similarly, but with the vertical edges of the piece 25 located farther towards the front than the vertical edges of piece 17 and the vertical edges of the piece 26 located farther toward the rear than the vertical edges of piece 22, so that the vertical edges of the two pieces 25 and 26 abut to form even joints. It will be understood that instead of the terry cloth used for this purpose, I may use a flexible leather and in fact, if desired, I may use such leather for all the outside surfaces of the finished shoe. The undersides of these two pieces 25 and 26 are now dusted with plaster of Paris, and after a very generous coating of the 75

latex has been applied on the pieces 17 and 22 the terry cloth pieces 25 and 26 are caused to adhere thereto and conform to the curvatures of the foot, as defined in the pieces 17 and 22. There will, of course, be a pucker and cut out at the front of the terry cloth piece 25 like the cut out 21 in the front piece 17. The whole top surface of the terry cloth on the shoe is now dusted with plaster of Paris and there is then brushed into the terry cloth surface a layer of the latex of the character above referred to, except that it is preferably a thinner liquid having a consistency substantially that of thick milk. This will set on the surface carrying the plaster of Paris to produce a gel. The formation of the gel can be expedited by applying an electric fan to produce a current of air for this purpose, for approximately 15 minutes or any other desired time, which will be sufficient to enable the 10 shoe to hold its shape or set, especially due to the drying effect on the latex of the plaster of Paris and due to any chemical effect of the plaster of Paris on the materials suspended in the latex. The wearer now rests the calf of his leg horizontally on a cushion on a stool located on the said 15 table. Thereupon, by means of a pencil, a design line, for trimming off the margin of the pieces 14, 17 and 23, is drawn around the margin of the sole or platform desired to indicate the position of the 20 outer edge of the pieces 17 and 23 to be retained in the shoe when finished. This outer edge may provide a platform for the shoe having different thicknesses, as hereinafter referred to, around different portions of the foot, if desired, but the 25 said outer edge line will in any event be located preferably above the line of greatest width, of the pad. The marginal portion of the layer 14 which has been fastened in place by the latex layer 15 is then loosened up around the pad and the edge 30 thereof is trimmed off down to the design line made with a pencil, just referred to. The pad 1 is now removed from the layer 14, leaving the pyramid 16 with a cofferdam formed by the margin of the set layer 14 which retains its position due 35 to the latex on the underside resulting from applying the latex 15 and the latex that has been applied to the other side of the layer 14. This leaves on the undersurface of the shoe, after the removal of the pad as aforesaid, a surface which is 40 then coated with the latex while the fabric is supported against the undersurface of the foot, including the toes, thus further aiding in retaining the position and shape of the toe-recess pyramid and the cofferdam. 45

I now mix a mud of any desired character, which will set or harden within the cofferdam formed beneath the shoe as well as in the pyramid 16 therein and which, for instance, may be made with any desired finely divided filling material, such as wood flour, etc. For this purpose, by way 50 of example, I may mix with any of the different forms of latex, but especially neoprene latex, 2 parts by volume of cork flour, 4 parts by volume of balsa wood flour and 1 part by volume of pine wood flour. It is found that this composition is desirable as the cork flour alone causes the latex to gel too fast and the balsa wood flour alone causes the latex to gel too slowly, although cork flour or balsa wood flour can be used alone. The 55 pine wood flour aids in the smooth spreading of the mud with a spatula. These proportions can be varied widely, in accordance with the chemical and gelling properties of the particular latex used, or for any other reason. Furthermore, the pine wood flour can be omitted, if desired, or pine

wood flour alone can be used with natural or any other latex. Also, cork wood flour alone could be used or balsa wood flour alone as a filling, although they have certain disadvantages when used alone, as referred to above. The wood flour is mixed with the thick latex in sufficient quantity up to a point where the material just begins to be shred-like but while still remaining plastic. This mixture is preferably made homogeneous by mixing the same in a bowl with a spoon. While the shoe is still on the foot, but with the leg extended horizontally over the stool, a layer of thick latex is applied to the whole undersurface of the pyramid and the enclosure made by the cofferdam formed by the edge of the layer 14, including the extreme edge thereof, which may have therein layers of many fabrics comprising the marginal portion of the cloth 14 and the marginal portions of the pieces 17, 22, 25 and 26. With the spatula the mud is buttered into the pyramid and cavity formed by the cofferdam, as shown in Fig. 22, the upper part of the shoe acting as a baffle formed by the more or less hardened plastic materials used in producing the said upper portion of the shoe, until preferably a crown, more or less, is formed at the outer surface of the cofferdam at the discretion of the operator. The entire top or outer surface of the mud is now made wet with a layer of the thick latex, the spatula being used to smear the latex and mud into the crevices, as desired, while it is very wet. The outer surface of the mud is now again made wet with another layer of thick latex and a burlap piece 27 is applied to cover the whole undersurface of the shoe, as shown in Figs. 2 and 22, the burlap having been previously powdered onto the top side thereof with plaster of Paris and being applied against the wet outer surface of the mud. This mud is allowed to set for about five minutes, a fan being used to aid the setting, if desired, until a soft but more or less stiff plastic is formed from the mud. The excess margin of the burlap piece 27 is now trimmed off to conform with the margin of the layer of cloth 14. Thereupon the foot is lowered onto the table with the leg vertical and the weight of the leg or body is allowed to press on the shoe while the wearer is sitting or standing. The weight of the wearer being more or less applied to the shoe in this way, will not only produce a flat undersurface for the sole of the shoe but will also complete the accurate conformation of the pyramid 16 between the toes and the sole of the foot, due to the entry of the moldable plastic mud into the interstices of the pyramid cavity beneath the layer of monks cloth 14. In addition, the weight thus applied to the shoe, which is resting on the table, gives to the shoe the correct angular position of the foot to the supporting surface of the table, resulting in the sole of the shoe taking on, at the different portions of the latter, varying thicknesses to provide and retain the natural angular relation between the individual foot and the supporting surface of the shoe, which, in this instance, is the top of the table. This retention in the shoe of the natural angle of the particular foot to the floor or other supporting surface could not accurately be provided by mere theoretical calculation in the building of a shoe. In other words, the upper portion of the shoe, which is on the foot above the sole or cavity containing the mud, produces a baffle holding the upper portion of the foot in the correct position in which it was formed by the presence of the supporting pad 1, and after the removal of the supporting pad 1 and the molding of the body of mud beneath 75

the foot while the foot is supported within the baffle on the upper portion of the foot, a shoe is obtained conforming accurately to the natural contours of the foot.

With a pencil, a line 28 is now drawn around the upper portion of the shoe indicating the upper shoe line to which the top of the shoe is to extend, this line being preferably located below the ankle bone and extending around the tendon at the rear of the foot. Another pencil line is now made down the upper ridge portion at the front of the foot and the shoe is then cut open down this ridge line with a pair of scissors, as shown in Fig. 3. The shoe is thereupon opened out a little along the ridge line and the foot is lifted out of the shoe. A little of the latex is now placed on one of the edges at the ridge line and a little plaster of Paris is placed along the opposite edge at the ridge line and the two edges are joined together temporarily thereby so as to preserve the shape of the shoe. Thereupon the shoe is turned over with the sole portion pointing upwardly, the whole bottom of the shoe is painted with the thick latex and a piece of terry cloth 29, having the underside which is to be applied to the shoe powdered with plaster of Paris, is now placed over the bottom or sole portion of the shoe and the shoe turned over into its upright position. The edges of the layer 29 are then trimmed off flush with the edges of the sole portion of the shoe and the materials of the shoe are allowed to set in the air with the aid of a fan, or not, for about three hours. Thereafter, the shoe is turned upside down again, a small amount of the plaster of Paris is dusted over the bottom of the shoe and a thin latex is then brushed thereon. Due to the plaster of Paris powder, the outer surface of the sole of the shoe can be built up in this way by alternate applications of the plaster of Paris and latex to give the desired thickness on the bottom of the shoe for obtaining the desired wear. Strings are now attached to the irregular edges of the upper portion of the shoe and the shoe is hung thereby in a drier or in the atmosphere, preferably, for twelve to twenty-four hours. After this, the upper edge of the shoe is trimmed around the marginal line 28 previously drawn for this purpose, as above referred to, and the shoe is also cut open along the upper ridge line, and along each side of the upper ridge line a marginal portion, which may be about $\frac{1}{8}$ " in width, is cut off in order to effectively reduce the size of the shoe and furnish, as a consequence, an effective fit of the foot on which it was made. The upper edges of the shoe, both along these marginal cut outs of the ridge line and along the topmost edge of the shoe, can now be finished by applying a little latex thereto. Eyelets 30 are now provided along both sides of the ridge line in the shoe to provide holes for laces 31 therein.

Now the shoes are placed on the individual for whom they were made and are worn a little but not too violently in the first two days, for instance a few steps merely being taken on the first day. After the third day the shoes can be worn outdoors by walking or even running but the materials therein have not by that time completely set, so that the wearing of the shoes in this way will cause them to acquire a dynamic shape of the feet in action. The materials in the shoes will have completely set within ten days, however.

An electrical conductor 32, in the form of a soft metal wire or a wire formed into a strand with some textile fibre, as for instance cotton, may now be inserted, going entirely through the shoe so

as to form an electrical contact between the body and the ground to minimize or eliminate heating of the feet.

The entire shoe may now receive any desired decoration, as for instance by spraying on a rubber cement and applying over the shoe a powder of any desired material having any desired color, as for instance a bronze powder. Any other desired decoration can be incorporated in the shoe, if desired, as for instance by introducing a dye into the latex or by locating one or more cords underneath the outermost layer, as for instance as shown in my Patent No. 2,332,000, upon Method of Manufacturing Shoes, granted October 19, 1943. Furthermore, if found desirable, the upper margin of the shoe can be provided on the inside of the shoe with a finishing strip of leather or other material 33.

The above procedure may be modified, if desired, to complete the shoe, by a different sequence of steps. The procedure for this purpose may be exactly the same as above described up to and including the point where the two layers of terry cloth 25 and 26 are applied to the outside of the shoe. Thereafter the procedure would be different to the following extent. The shoe may be cut down the front thereof opposite the top front ridge line of the foot, and the foot then removed from the shoe. The two edges formed by cutting on the ridge line may then have marginal portions removed from each of the same by a $\frac{1}{8}$ " or other width of the material, as above described, and the two resulting edges of the shoe may be then stuck together, also as above described, by applying plaster of Paris and latex to the two edges, respectively. The pad 1, it will be noted, is still in the shoe. The shoe is then set up in front of a fan, or in the air without a fan, for about two hours to allow the materials to partially set. The terry cloth on the outside of the shoe is then dusted over with plaster of Paris and latex is brushed thereon and the shoe allowed to remain in a current of air from the fan for several hours. The edges of the shoe, at the top thereof, are now trimmed down to the line 28 in the manner previously described and the shoe is opened down the front line corresponding to the ridge line. The eyelets 30 and laces 31 are now introduced along the two edges near the ridge line and the shoe is allowed to stand until the next day, to allow further preliminary setting of the materials. After this, the pad 1 is removed from the upper by stripping the edges of the layer 14 loose therefrom and trimming down the said edges to form the cofferdam along the design line, as previously described. After this, the individual wearer puts on the portion of the shoe thus obtained and laces it up. From this point on, the modified form of the process is exactly the same as, after the removal of the pad 1 as in the process previously described herein, the cofferdam formed by the edge of the layer 14 is then filled with the mud and subjected to the pressure produced by the weight of the leg or body to form effectively the pyramid and fit the contours of the foot while the upper portion of the foot is retained firmly in position by the more or less hardened materials which have been used in producing the upper portion of the shoe, so that the latter forms a baffle during the molding of the lower or sole portion of the shoe against the undersurface of the foot.

While I have described my invention above in detail I wish it to be understood that many changes may be made therein without departing

from the spirit of the same. For instance, the fabrics used may be substituted by any other desired fabrics. Also, the shoe can be built on a foot form such as a cast or last conforming to the shape of the foot but, of course, not so advantageously, especially in regard to the conformation of the sole portion of the shoe. When proceeding in this way, however, a foot support having the shape of the foot outline need not be used.

I claim:

1. The process which comprises providing a convex support, comprising a container of finely divided flowable material, for the bottom of a foot substantially conforming to the marginal outline thereof, building an upper having a flexible underneath layer attached thereto containing a toe-recess pyramid pushed up into said layer on the foot, the upper being built while the foot is on and supported from said support, applying latex to said layer during the process, removing the support from said layer after allowing the setting of the latex, and introducing into the space left by the removed support a plastic moldable mass of supporting material, conforming the plastic mass to the outwardly directed surface of said layer while the plastic is moldable and allowing the plastic to set.

2. The process which comprises providing a convex support, comprising a container of finely divided flowable material, for the bottom of a foot substantially conforming to the marginal outline thereof, building an upper having a flexible underneath layer attached thereto containing a toe-recess pyramid pushed up into said layer on the foot, the upper being built while the foot is on and supported from said support, applying latex to said layer during the process, said upper being made out of a sheet material and a rubber-like binder, removing the support from said layer after allowing the setting of said latex, pushing the underneath layer up into the pyramidal cavity at the rear of and between the toes and introducing into the space left by the removed support a plastic moldable mass of supporting material, allowing the binder to harden, conforming the plastic to the contours of the bottom of the foot beneath said layer while the plastic is moldable and allowing the plastic to set after allowing the weight of the foot to press thereon.

3. The process which comprises providing a convex support, comprising a container of finely divided flowable material, for the bottom of a foot substantially conforming to the marginal outline thereof, building an upper having a flexible underneath layer attached thereto containing a toe-recess pyramid pushed up into said layer on the foot, the upper being built while the foot is on and supported from said support, applying latex to said layer during the process, removing the support from said layer after allowing the setting of the latex, trimming off the edges of the underneath layer to the desired width to form a cofferdam, and introducing into the space left by the removed support a plastic moldable mass of supporting material.

4. The process which comprises providing a convex support, comprising a container of finely divided flowable material, for the bottom of a foot substantially conforming to the marginal outline thereof, building an upper having a flexible underneath layer wider than said upper on the foot, the upper being built while the foot is on and supported from said support, applying latex to said layer during the process and sticking the

11

margin of the underneath layer to the pad while forming puckers which are cut off, removing the support from said layer after setting of the latex, and introducing into the space left by the removed support a plastic moldable mass of supporting material, conforming the plastic mass to the outwardly directed surface of said layer while the plastic is moldable and allowing the plastic to set.

5. The process which comprises building an upper on a foot having a sheet of material on the underside thereof, which was pushed up manually into the pyramid located between the toes and the ball of the foot, applying latex to the said sheet of material, said upper to the margin of said sheet, and introducing a plastic into 15

12

neath portion of the foot to produce a sole when hardened.
